UNITED STATES PATENT OFFICE.

JOHN H. MATCHETT AND FRANK A. NEFF, OF OAKLAND, CALIFORNIA.

MASSAGE VIBRATOR.

Application filed June 25, 1925. Serial No. 39,446.

To all whom it may concern:

Be it known that we, JOHN H. MATCHETT and FRANK A. NEFF, citizens of the United States, residing at Oakland, in the county of Alameda and State of California, have invented certain new and useful Improvements in Massage Vibrators, of which the following is a specification.

Our invention is a massage vibrator in which a plurality of massaging and vibrating buttons are mounted on a drum which may be shifted or rolled over a person's body and therefore cause a vibration with a slight massaging movement.

Our invention is directed to a manner of not only giving reciprocatory vibrations but to move the massaging buttons over the body with the movement of translation thereby combine the vibration with the massaging effect.

The vibrator as a whole is constructed with an electric motor which has a pair of casings secured to the opposite ends and a spider shaped device having a plurality of arms with buttons on the ends thereof are mounted on eccentrics on the motor shaft so that the buttons are given a reciprocating motion, the stems supporting the buttons operating through slots in the casing. The movement of translation or peripheral movement is caused by a fixed pin engaging a slot in the spider and thereby forcing all the arms or stems to have a somewhat circular motion which, for the most remote buttons, will give an oval motion, so that the buttons will be drawn along a person's body when undergoing a treatment.

Our invention will be more readily understood from the following description and drawings, in which:

Figure 1 is a longitudinal section of our vibrator taken on the line 1—1 of Figure 2 in the direction of the arrows.

Figure 2 is an end view of Figure 1 in the direction of the arrow with the end casing cap and handle removed.

Figure 3 is a detail section of Figure 2 on the line 3—3 in the direction of the arrow.

Figure 4 is a diagrammatic view of the spider, the arms and the eccentric and guiding slot to illustrate the movement of the vibrating buttons.

The vibrator has a driving motor 1 in which the laminated fields 2 form one part of the periphery and the casings 3 and 4

are secured onto each end of the motor frame 5, which latter is fastened to each side of the field by bolts 6. The angularly bent bolts 7 which are part way screwed into the fields as indicated by 8, and having a sharp angular bend 9 pass through apertures 10 in the partition wall 11 of the casings 4. Nuts 12 threaded on the straight portion 13 of the angularly bent bolts 7 secure the casings 3 and 4 on opposite ends of the motor.

The motor shaft 14 is journalled at 15 in the partition wall 11 and has secured to each end a detachable eccentric block 16 secured in place by set screws 17, the eccentric portion 18 being on the inner face. A spider 19 having a series of arms 20 with reduced stems 21 extending radially from the body of the spider is fitted on the eccentric, the stems extend through slots 22 in the casing through grooves 23 which are for the purpose of assembly. Buttons 24 are secured to the ends of the stems and are preferably dome shaped and form the massage elements.

The spider has a web portion 25 with a slot 26 therein through which extend fixed pins 27 being secured to lugs 28 formed integral with the partitions 11. A washer 29, a steel guide block 30, and an outer washer 31, are placed over the ends of the pins 27 and held therein by means of the spring 32 bearing against the stop plate 33 which is held in position by cotter pins 34. The steel guide block 30 fits against the sides of the slot 26 and forms a bearing for the reciprocating motion of the web part 25 of the spider.

Referring to Figure 4 it will be seen that the eccentric causes the arms to move in and out in a radial direction and on account of the pivoting and sliding motion of the spider relative to the fixed pin 27 the ends of the stems, or the buttons, are also given an oscillatory movement in somewhat of a peripheral direction. The combination of these movements causes any particular point of the buttons to travel in a circular or flat oval path. It will be noted that the buttons on the side nearest the fixed pin have a substantially circular motion and that the two extreme left and right buttons have a more elongated path and that the two upper or most remote buttons have a more pronounced oval path. Therefore, a person undergoing a massaging treatment may have the buttons give a vibratory motion or combine this

with the smoothing or slight rubbing motion. It will be understood that the vibrations are of small degree but are very rapid in accordance with the rotation of the motor and that the eccentric block 16 may be changed to either increase or decrease the vibration.

A pair of end caps 35 and 36 are secured to the housings by means of nuts 37 engaging the outer ends of the straight portion 13 of the bent bolts 7. These caps are both substantially the same. A handle 38 is mounted at one end having a bolt 39 secured through the cap 35 and forming a swivel for the handle. The other handle 40 has a sleeve 41 secured thereto and an insulating block 42 secured thereto by screws 43, a neck 44 of the wooden handle 45 being secured by screws 46. The inner end 47 of the insulating block 42 is enlarged so as to bear against the inside face of the cap 36 and thereby allow the handle 40 to swivel.

The purpose of the swiveling handles is to allow the operator to hold the device in each hand and roll it slowly over a person's body so that they will be subjected to the vibration and the massage in this treatment.

The electrical connections to the motor are substantially as follows:

The electric leads 48 are carried on an insulated cable through the handle 40 and are divided, one terminal 49 being connected to a ring 50, whereas the other central terminal 51 ends at a central button 52, these wires passing through suitable passages in the insulated block 42. A contact 53 supported on the spring arm 54 which is rigidly secured to a lug 55 fastened to the partition 11 carries the current from the ring to a lead 56 extending to the motor. A contact 57 on the spring arm 58, which is secured to a lug 59 connected to the partition 11 takes the current from the central button 52 to the other terminal of the motor. It will thus be seen that this arrangement provides sliding contacts taking the current through the handle and the rotating casing and cap to the electric motor.

Apertures 60 in the partition 11 and 61 in the caps 35 and 36 are for the purpose of ventilation and the small passage 62 is for the purpose of oiling the motor shaft.

The manner of use of our device will be obvious. The electric current will be switched on and off by a switch external to our vibrator and the whole device may be lightly rolled or moved over a person's body and they may thus be treated with both the vibratory and massaging movement at one and the same time. Although these movements are very slight they are so rapid as to have beneficial results, which are more marked than a straight reciprocatory vibration and than a straight movement of translation having a massaging effect.

Our invention may be materially changed, for instance by installing more or less vibratory elements and in changing the type of motion of such elements without departing from the spirit of our invention.

Our invention is an improvement or an adaptation of the foot vibrator shown in our patent application Serial No. 34,008 filed June 1, 1925, and co-pending with this application.

Having described our invention, what we claim is:—

1. A massage vibrator comprising in combination a plurality of vibratory button-like elements, a drum shaped device in which said elements are mounted, handles by which said drum shaped device and the buttons may be rolled and means situated in said drum shaped device for operating the button-like elements.

2. A massage vibrator comprising in combination a cylindrical casing, an electric motor situated therein, an eccentric on the motor shaft, and a vibrating element having a series of buttons extending beyond the casing, and handles swiveled to the casing whereby the whole device may be rolled over a person's body.

3. A massage vibrator, as claimed in claim 2, in which a fixed guide element is secured to the casing and extends into a slot in the vibrating element.

4. A massage vibrator comprising in combination an electric motor, a cylindrical casing fixedly secured to the end thereof, an eccentric fixed to the shaft of the electric motor, a spider fitted on said eccentric and having a series of radial arms extending through slots in the casing, massage buttons secured to the ends of the arms and electric leads to and from the motor.

5. A massage vibrator, as claimed in claim 4, having in addition a slot in the spider and a pin secured to the casing fitting within said slot to force the buttons into a combined radially reciprocating and peripherally oscillating movement.

6. A massage vibrator, as claimed in claim 4, having in addition a cap secured to the casing and a handle swivelly mounted on the cap.

7. A massage vibrator, as claimed in claim 4, having in addition a similar casing, a vibratory device at the opposite end of the electric motor, caps secured on such opposite casings, handles swiveled to said caps and means attached to said casings to force the massage buttons in a combined radial reciprocating and peripherally oscillating movement.

8. In a massage vibrator comprising a drum shaped device, a plurality of arms extending radially through said device, massage buttons on the ends of said arms, means to vibrate said buttons radially and means

to combine with such vibration a peripheral oscillation whereby the buttons describe an oval path.

9. In a massage vibrator, as claimed in claim 8 an electric motor mounted in the drum shaped device and an operative connection from the drums to the arms to reciprocate the arms.

10. In a massage vibrator, as claimed in

claim 8, having an electric motor mounted in the drum shaped device, eccentrics attached to the shaft of said motor and an operative connection between said eccentrics and the arms.

In testimony whereof we affix our signatures.

JOHN H. MATCHETT.
FRANK A. NEFF.
